(57) **CLAIM**

The ornamental design for a cement mixing paddle, as shown and described.

DESCRIPTION

FIG. 1 is a front perspective view of a cement mixing paddle

FIG. 2 is a left-side view thereof

FIG. 3 is a right-side view thereof

FIG. 4 is a front view thereof

FIG. 5 is a rear view thereof

FIG. 6 is a top view thereof; and,

FIG. 7 is a bottom view thereof.

The broken lines shown are included for the purpose of illustrating environmental structure and form no part of the claimed design.
